UNITED STATES PATENT OFFICE.

TOKUTARO SUZUKI, OF YOKOHAMA, JAPAN.

INTERSTICED CRUSH-HAT.

1,196,823.

Specification of Letters Patent. Patented Sept. 5, 1916.

Application filed May 29, 1915. Serial No. 31,190.

To all whom it may concern:

Be it known that I, TOKUTARO SUZUKI, a subject of the Emperor of Japan, residing at No. 204 Minami Yoshida-Cho, city of 5 Yokohama, Empire of Japan, have invented certain Improvements in Intersticed Crush-Hats, of which the following is a specification.

This invention relates to improvements 10 in hats particularly to hats made of Manila hemp or vegetal fiber which is finished and made up to form open crochet like figures or scroll work.

It is the object of the present invention 15 to provide a hat of this kind with an exchangeable colored lining allowing a variation in the appearance of the hat according to the color chosen for said lining.

In order that this invention may be 20 clearly understood and more readily carried into practice, I have appended hereunto a sheet of drawing illustrating the preferred form of my improved hat shown in perspective.

25 In carrying my invention into practice, I employ as a braid vegetal fiber of Manila hemp 1 which I twist or plait together or work like Cluny lace, renaissance, crochet

work, or the like or a combination thereof so as to form open spaces through which 30 the color of a lining 2 is shining. This lining is made detachable and exchangeable so as to produce a change in the appearance of the hat by suitably changing the lining from one color to the other and thus creating 35 the impression that wearer wears a different hat every time he changes the color of the lining.

Besides being suitable for hats for ladies or gentlemen the invention is equally well 40 applicable in the manufacture of paralettes or the like.

What I claim is:—

A hat of the character described comprising in combination a body of vegetal 45 fiber made to form open crochet figures and an exchangeable colored lining for said body for varying the appearance of the hat, substantially as described.

In witness whereof I affix my signature 50 in presence of two witnesses.

TOKUTARO SUZUKI.

Witnesses:

GENJI HUTIBARA,
HARUTADA YUSUMANA.
